UNITED STATES PATENT OFFICE.

WILLIAM TWEEDDALE, OF BROOKLYN, ASSIGNOR TO THE J. L. MOTT IRON WORKS, OF NEW YORK, N. Y.

DESIGN FOR A STATUE.

SPECIFICATION forming part of Design No. 20,021, dated July 15, 1890.

Application filed June 14, 1890. Serial No. 355,505. Term of patent 7 years.

To all whom it may concern:

Be it known that I, WILLIAM TWEEDDALE, a citizen of the United States, residing at Brooklyn, in the county of Kings and State of New York, have invented and produced a new and original Design for a Statue, of which the following is a specification.

The leading feature of my design consists in the representation of a conical pile of stones 10 B, with the representation of an alligator C upon such conical pile, with the head elevated, and with a serpent D coiled around the body and with the neck extending outwardly and the head turned toward the head of the alligator, as represented in the accompanying photographic view.

I claim as my invention—

The design for a statue herein shown and described, the same comprising the representation of a conical pile of stones with the representation of an alligator thereon, and the representation of a serpent coiled around the representation of the alligator, substantially as set forth and shown.

Signed by me this 11th day of June 1890.

WILLIAM TWEEDDALE.
